[57] CLAIM

The ornamental design for a bottle, as shown and described.

DESCRIPTION

FIG. 1 is a front elevational view of a bottle showing my new design;

FIG. 2 is an elevational view looking from the left of FIG. 1;

FIG. 3 is a rear elevational;

FIG. 4 is an elevational view looking from the right of FIG. 1;

FIG. 5 is a top plan view;

FIG. 6 is a bottom plan view;

FIG. 7 is a top perspective view; and

FIG. 8 is another top perspective taken from the corner diagonally opposite to that from which FIG. 7 is taken.

FIG.2

FIG.1

FIG. 5

FIG. 6

FIG. 4

FIG. 3

FIG. 8

FIG. 7
